UNITED STATES PATENT OFFICE.

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK.

MULTIPLEX-SIGNALING SYSTEM.

Application filed October 2, 1920. Serial No. 414,292.

To all whom it may concern:

- Be it known that I, BURTON W. KENDALL, a citizen of the United States, residing at New York, in the county of New York and 5 State of New York, have invented certain new and useful Improvements in Multiplex-Signaling Systems, of which the following is a full, clear, concise, and exact description.
- 10 This invention relates to multiplex signaling systems and more particularly to signaling systems in which a plurality of Morse code messages may be simultaneously transmitted over a common circuit each as 15 variations or interruptions of oscillations of a particular frequency individual to that message.
- A feature of the invention consists in the provision of a common trunk line or link 20 circuit with apparatus permitting it to serve simultaneously to connect a number of pairs of two-way Morse telegraph lines.
- A further feature of the invention consists in the provision of a multiplex 25 signaling system using oscillations of an individual frequency for each message, with means for translating the different frequency oscillations into other oscillations of relatively large frequency difference.
- 30 According to this invention, a common transmission circuit or trunk line is associated with a plurality of Morse lines in such manner that each Morse line repeats its outgoing message impulses to the transmission circuit as oscillation trains of corresponding duration and of an oscillation frequency peculiar to that particular Morse line. The common transmission circuit repeats to each Morse line as Morse code impulses of corresponding duration, such incoming oscillation trains as are of the oscillation frequency peculiar to that particular Morse line. In order to repeat the Morse 40 impulses to the transmission circuit, the receiving relay of the Morse line is caused to control the association of an oscillator with the transmission circuit so that when the relay is energized by a code impulse, the oscillator is operatively associated with 45 the circuit and transmits thereover a train of waves of its distinctive frequency. The oscillators are associated by individual circuits with the transmission circuit in such manner that the operation of each is unaffected by the others. The receiving chan-
- nels for repeating messages from the common transmission circuit to the Morse lines are each selective of oscillations of a particular frequency to the substantial exclusion of those of different frequency. In 60 order to increase the relative difference in frequency of two adjacent frequency transmissions, the incoming oscillations may be combined with oscillations produced by another source, preferably at the receiver, as 65 in order to secure oscillations of the difference frequency of said incoming oscillations and said locally produced oscillations. These resultant difference frequency oscillations may be made to differ in frequency 70 by relatively larger amounts than the transmitted oscillations and are thus more readily separable.
- In the drawing, Fig. 1 illustrates diagrammatically circuit arrangements for associating one terminal of a common transmission circuit with a plurality of Morse 75 lines for multiplex operation; Fig. 2 illustrates a modified system in which an individual hybrid coil is provided for each 80 Morse line; Fig. 3, a further modification in which a local source at the receiver produces oscillations to interact with the received oscillations; and Fig. 4 is a detail diagram of the device for translating os- 85 cillation trains into impulses.
- Referring to Fig. 1, a terminal of a Morse line 1 with the usual artificial line A is shown associated with the terminal of a common transmission circuit 2. Receiving 90 relay 3 of the Morse line when energized operates its armature 4 to close the circuit of a relay 5, the armatures 6 of which are connected to the terminals of an alternating current source O, preferably, although not 95 necessarily, of the electron discharge type. When energized, relay 5 connects the oscillation source O to a tuned loop circuit 8 inductively connected to an outgoing channel 9 by a branch circuit 10, which, as in 100 the case of the circuit 8, is preferably tuned to the frequency of source O. Although but a single Morse line is illustrated, it is understood that a plurality of such lines are provided, each having its individual receiving relay and individual oscillator controlled thereby to supply oscillations of a frequency individual to that oscillator to a correspondingly tuned circuit 8 associated with the outgoing channel 9.

Outgoing channel 9 is connected with circuit 2 by means of a hybrid coil 11 of the type ordinarily employed in two-way conjugate repeating circuits. A balancing network N and the circuit 2 are symmetrically connected with respect to the mid-points of the hybrid coil and the network is so designed as to simulate the impedance of circuit 2 for currents of each of the frequencies transmitted thereover.

An incoming channel 12 is conjugately connected with circuit 2 with respect to the outgoing channel by an inductive coupling with the bridge circuit of the hybrid coil.

Associated with the incoming channel and preferably, although not necessarily, bridged thereacross, are a plurality of selective devices 13 corresponding in their selectivity to the tuned circuits 8 and 10.

These selective devices may take the form of the circuits 8, 10 associated with the outgoing channel or may be, as illustrated, band filters of the general type disclosed in U. S. Patent 1,227,113 to Campbell. The

characteristic of these filters is such that they transmit currents of a given range of frequencies with substantially negligible attenuation and suppress currents of frequencies outside the given range. This

range may be made very small but is preferably sufficiently wide to permit slight variations in the generator frequency. Currents selected and transmitted by band filter 13 are impressed upon the input circuit of

a translating device D, the function of which is to receive oscillation trains and to translate them into impulses of corresponding duration. Translating device D, when operated, supplies an energizing

impulse to a transmitting relay 14 which operates to close the ordinary Morse transmitting circuit 15 to cause direct current source 16 to impress code impulses on Morse line 1. The operation of this arrangement

is as follows: Morse code impulses impressed on line 1 at a distant point energize receiving relay 3 which in turn closes the energizing circuit of relay 5, thus connecting oscillator O to outgoing channel 9.

If, for example, the oscillator is producing oscillations of 8,000 cycles frequency, a train of waves of that frequency will be transmitted out over circuit 2. The duration of this train will correspond to that

of the code impulse on line 1. At the distant terminal of circuit 2, the apparatus is similar to that at the terminal associated with line 1 and includes several Morse lines, one of which corresponds to line 1. The

operation of this corresponding line and its apparatus in receiving may be clear from a consideration of the receiving operation of line 1. A train of incoming oscillations of 8,000 cycle frequency arriving over circuit 2 is transferred from the bridge of the

hybrid coil 11 to incoming channel 12. Of the various filters 13 connected with channel 12 all except that associated with line 1 are so designed as to exclude currents of 8,000 cycle frequency. The train of oscillations is therefore impressed upon the input circuit of only the translating device D which causes an impulse of corresponding duration to be supplied, from its output circuit to transmitting relay 14 which repeats the impulse to line 1. In this manner two Morse lines connected to opposite terminals of the common transmission circuit 2 are enabled to carry on two-way inter-communication over circuit 2 by means of the 8,000-cycle oscillations. As many pairs of Morse lines as are desired may thus be connected, the two lines of each pair being connected to the opposite terminals of circuit 2. It will be understood that each pair of lines employs oscillations of an individual frequency and that the various selecting circuits 8, 10, and 13 are designed each to transmit oscillations of the frequency employed by the particular apparatus associated therewith, and to exclude oscillations of other frequencies. However, the apparatus may be so designed as to use oscillations of one frequency for the outgoing transmission and oscillations of a different frequency for the return transmission to the same low frequency line. It is therefore possible to carry on an indefinite number of simultaneous two-way transmissions over the common transmission circuit 2 depending upon the transmission characteristics of this circuit for oscillations and the frequency difference which is necessary for separation of the oscillations of adjacent channels.

In Fig. 2 a Morse line is illustrated connected to common transmission circuit 22 by channels similar to those employed in the arrangement of Fig. 1 except that an individual hybrid coil is used for each of the Morse lines and the band filters are connected between the common transmission circuit 22 and their respective hybrid coils. In this arrangement a network N₁ is provided for each channel to simulate the impedance of the circuit 22 and its associated circuits as viewed from hybrid coil 19 for currents of the frequency traversing the hybrid coil. Incoming channel 17 includes translating device D and relay 14 and outgoing channel 18 comprises normally disconnected oscillator O. In all essential respects the operation of these Morse circuits is the same as in the previously described arrangement and accordingly requires no further explanation.

Where it is desired to use the common transmission circuit 22 for ordinary telephony or in effect to composite the system just described on an ordinary trunk line 22, 130

- an ordinary talking circuit including the subscribers' station shown conventionally as comprising a transmitter 20, a source 24 and a receiver 21 may be connected to circuit 22 by a filter 23 which transmits with substantially negligible attenuation currents of the essential speech frequency and substantially extinguishes currents of frequencies differing appreciably therefrom.
- 5 The transmission band filter 23 may be given various limits but it may be stated that in practice the range of from 100 to 2200 cycles is in general satisfactory. The Morse channels associated with filters 13 of
- 10 Fig. 2 may therefore employ oscillation frequency exceeding 2200 or less than 100 cycles in frequency. In some cases it is desirable to reserve the range of frequencies below 100 cycles for ordinary Morse.
- 15 20 signals which may be transmitted directly over the common transmission circuit as in the case of ordinary composited lines.
- The circuits of Fig. 3 are in general similar to those of Fig. 1 with the exception that 25 a frequency reduction apparatus is introduced between the circuit 2 and incoming channel 12. This consists of a balanced arrangement of evacuated electron discharge devices 24 having their grid circuits op-
- 30 positively related to the bridge circuit of the hybrid coil 11 so that one grid will tend to become positive with respect to the common filament potential when the other is made negative and vice versa. Similarly,
- 35 the plate circuits of these electron discharge devices are oppositely connected to the incoming channel 12, that is, so that an increase in the current of one tends to annul the effect of an increase in the current of
- 40 the other so far as channel 12 is concerned. A local source 25 of sinusoidal oscillations is connected to both electron discharge devices and as illustrated may be inductively associated with a transformer winding 26
- 45 in a common branch of their grid circuits. This arrangement is similar to the well-known combiner disclosed and fully explained in British Patent No. 131,426. It will be sufficient to point out that its characteristics are such that it does not transmit oscillations supplied by source 25 but when oscillations are received from hybrid coil 11, it transmits oscillations of the sum frequency and other oscillations of the difference frequency of the local oscillations and the incoming oscillations. If, for example, three Morse lines at the remote end of circuit 2 transmit thereover oscillations of 6500, 7000 and 7500 cycles, respectively,
- 55 60 and the local oscillator 25 operates to produce oscillations of 8000 cycles, there will appear in channel 12, when all three Morse circuits are simultaneously operated, difference frequency currents of 1500, 1000 and 500 cycles respectively, corresponding to

impulses from the three remote Morse lines. These difference frequency currents are much more readily separable than are the original currents transmitted over the circuit 2, for the reason that their relative 70 frequency difference is larger. For example, the intermediate original frequency 7000 differs from the other two original frequencies 6500 and 7500 by less than 10% and the corresponding intermediate difference frequency, namely, 1000 cycles, differs from the other two difference frequencies 500 and 1500 respectively, by 50%.

In the arrangement of Fig. 3, tuned selecting circuits are associated with the incoming and outgoing channels. It is to be understood that band filters may be used wherever selective circuits are shown. The frequency reducing arrangement of Fig. 3 may likewise be employed in the common incoming channel between the common transmission circuit and the selective or filter arrangement for separating the various transmissions in systems where ordinary telephone currents are also transmitted. 80 In such cases the speech frequency currents are first separated from the various other currents which then pass to the frequency reduction apparatus.

The translating device for receiving wave trains and producing uni-directional impulses of corresponding duration, shown conventionally in the first three figures by the rectangle D, is illustrated in detail in Fig. 4. It comprises two thermionic repeaters preferably of the highly evacuated three-element type, the first serving to amplify the wave train and the second operating in response to the amplified wave train to control relay 14. The normal potential of the grid or control element of the second repeater 30 is determined by a polarizing source 31, and the plate current voltage is obtained by a variable connection to source 32 which supplies plate current to 95 the first repeater. It is therefore possible to so adjust the circuits that the incoming oscillations will cause an increase in the average value of the space current, thus operating the marginal relay 14. It is also possible to make such adjustments that the average value of the space current is decreased. With this latter arrangement the marginal relay would normally be energized and would release its armature during the wave 100 train.

The invention has been described as embodied in conductive signaling systems but it is to be understood that although of particular utility in multiplex Morse code signaling over wire lines, the principles of the invention are applicable as well to energy transmission generally, whether by radiant energy or energy transmitted over conductive circuits.

What is claimed is:

1. In combination a multiplex wave transmission circuit, a plurality of continuously active wave sources of different frequencies for said circuit, distant outlying stations, a direct current telegraph line extending from each of said stations for cooperating with said transmission circuit in the transmission of signals and a relay actuated from each station by telegraphic impulses on the corresponding line for controlling the application to and withdrawal from said transmission circuit of the wave from the corresponding source, for time periods in accordance with the length of said impulses.
2. In a telegraph system distantly separated main stations, a multiplex carrier line interconnecting said stations, a number of outlying stations connected with each main station by direct current telegraph lines terminating in Morse telegraph receiving and sending sets including relays, a number of continuously active wave sources at each of said main stations for furnishing waves of different frequencies for transmission over said multiplex carrier current

line, carrier current receiving circuits at each main station for selectively receiving waves of the frequencies generated at a distant main station, said carrier current receiving circuits including relays, each of said wave sources at each main station being under control of a Morse receiving relay of one of said telegraph lines, each of said Morse sending sets for the telegraph lines being under control of a carrier current receiving relay, said wave sources at the respective main stations and the carrier current receiving circuits being allotted so that an outlying station transmits signals to and receives signals from a given outlying station that is associated with another main station, through the medium of said multiplex carrier current line and by means of a wave source and a carrier current receiving circuit at each main station.

In witness whereof, I hereunto subscribe my name this 28th day of September A. D., 1920.

BURTON W. KENDALL.
